UNITED STATES PATENT OFFICE.

LUDWIG VON ORTH, OF BERLIN, GERMANY, ASSIGNOR TO DEUTSCHE SCHIFFS FEUERLÖSCHGESELLSCHAFT MIT BESCHRÄNKTER HAF-TUNG, OF BREMEN, GERMANY.

APPLIANCE FOR STORAGE VESSELS FOR LIQUID GASES.

No. 830,248.

Specification of Letters Patent.

Patented Sept. 4, 1906.

Application filed April 1, 1904. Serial No. 201,125.

To all whom it may concern:

Be it known that I, LUDWIG VON ORTH, engineer, a citizen of the Kingdom of Württemberg, Germany, residing at No. 9 Ludwigs-kirchstrasse, Berlin, in the Empire of Germany, have invented certain new and useful Improvements in Appliances for Storage Vessels for Liquid Gases; and I do hereby declare the following to be a full, clear, and exact description of the invention, such as will enable others skilled in the art to which it appertains to make and use the same.

When withdrawing liquid gases, such as liquid carbon dioxide and the like, from the storage vessels or bottles, the reducing-valve becomes readily frozen, as is well known, and the discharge-openings become clogged with snow. In order to obviate this disadvantage, various simple means have been employed, which were all based upon the idea of warming the liquid gas from the outside. The simplest means employed consists in that the reducing-valve has a warm rag wrapped round it. Another means consists in warming the liquid gas in the receptacle by passing steam or other heating medium through it, and a third known means consists in providing between the carbon-dioxide bottle and the reducing-valve a water-chamber that can be heated, through which the carbon-dioxide conduit is made to pass. For the requirements of a moderate discharge of the liquid gas as heretofore effected these means are sufficient. They are, however, quite insufficient when large quantities of the liquid gas are to be discharged very rapidly from the storage vessels—such, for instance, as in the case of extinguishing fires on board ship or the like by means of carbon dioxide. With such a large consumption of carbon dioxide a heatable water-chamber, such as before mentioned, would not be of the least use. It would require to be of the size of a large steam-boiler and would then possibly not be effective. In addition, such a heatable chamber between the carbon-dioxide vessel and the reducing-valve could not be practically applied in cases such as above mentioned, as the heating up of the water would require several hours, as in the case of an ordinary steam-boiler, during which time the conflagration would require to have been completely extinguished. On the other

hand, the use of such a source of heat between the carbon-dioxide vessel and the reducing-valve would be a source of very great danger, as in the event of the consumption of carbon dioxide being stopped from any cause a prejudicial increase of the heating action upon the carbon dioxide contained in the receptacle would take place and easily result in an explosion.

The present invention has for its object to prevent the freezing of the liquid gas in such cases where a rapid consumption of large quantities of carbon dioxide or the like takes place, while at the same time the arrangement is capable of being put rapidly into effective operation and is capable of automatic regulation. This is attained by the use of a source of heat, as before; but the main difference between this and what has been proposed consists in that the gas is not heated in its liquid condition, as heretofore, but only after its issue in the vaporized condition. The heating medium is then brought in contact with the gas in a fine state of subdivision and can consequently act much better thereon without any danger of the heat being carried back to the storage vessel, as only the gaseous particles are heated that have already issued therefrom. An arrangement for carrying out this method of heating is shown diagrammatically on the accompanying drawings, in which—

Figure 1 shows a vertical longitudinal section. Fig. 2 shows a cross-section, and Fig. 3 shows the apparatus attached to a storage-chamber.

The liquid gas issues through a pipe or nozzle *a* from the storage vessel *1*. This pipe opens into a second pipe or chamber *b*, passing through a vessel or casing *c*. Into the vessel a liquid-heating medium is introduced at *d*, whence it flows over the ribs *e*, projecting from the pipe *b* in such manner as to flow in a serpentine direction round the pipe *b* and to issue at *f*. The pipe or nozzle *a* is closed at its end and has an oblique or spirally-formed passage *g*. In consequence hereof the issuing liquid gas is directed or discharged at an angle directly against the inner wall of the pipe *b*, against which it impinges under pressure, so as to be dispersed and converted into vapor in consequence of the enlarged space afforded by the pipe or chamber

b as compared with the opening of the passage *g*. The gas thus formed then flows in a helical path downward through the pipe or chamber *b* under continual expansion. The 5 gaseous current therefore comes in contact with the entire inner surface of the pipe, so that the gaseous particles are continually heated by contact with the pipe. Thus a reliable and considerable heating action is obtained, while any backward action upon the 10 storage vessel is prevented by the pipe *a*. The ribs of pipe *b*, inclosed in the casing *c*, not only serve for guiding the current of the heating medium, but they also serve to transmit directly by their conducting power the 15 heat of the liquid medium to the pipe or chamber *b*, which in addition is also heated externally by contact with the medium.

As heating medium water of ordinary 20 temperature is advantageously employed, so that no special source of heat is necessary. The reason why water can be used as an energetic heating medium, although, as is known, it is colder than the liquid carbon dioxide, is that such heating medium is not required to warm up the liquid carbon dioxide as heretofore, but is made to surround the finely-divided vaporizing gases. The 25 production of cold only occurs at the moment of vaporization, and the freezing is produced by the backward conduction of the cold. The fact that in the arrangement shown by way of example the pipe or nozzle *a* reaches to a 30 certain extent into the casing or vessel *c* has no effect upon the action. It is only done out of practical considerations in order that the pipe or nozzle *a* may fit closely and tightly into the heating device. No heating of the 35 liquid carbon dioxide in the pipe or nozzle *a* will take place, because the carbon dioxide flows too rapidly through the pipe or nozzle *a* (in about one-hundredth of a second) and because, as already stated, the heating medium 40 can be colder than the liquid carbon dioxide.

Having thus described the nature of my 45 said invention and the best means I know of carrying the same into practical effect, I claim—

1. In a means for preventing the freezing and formation of snow on the discharge of 50 large quantities of liquid gas, such as carbon dioxide, from storage vessels, the combination with a vessel containing a suitable heating medium for the vaporized gas, of a chamber therein, and a nozzle for the liquid gas discharging directly against the wall of the chamber.

2. In a means for preventing the freezing and formation of snow on the discharge of 55 large quantities of liquid gas, such as carbon dioxide, from storage vessels, the combination of a discharge-pipe, such as *a*, having an oblique passage *g*, a pipe, such as *b*, of larger diameter communicating with the discharge-pipe and serving as a heating-surface upon 60 which the gas impinges and over which it is made to flow in a helical path while being expanded and vaporized, ribs, such as *e*, formed on the pipe *b*, and a casing, such as *c*, surrounding the pipe *b* and the ribs, and through 65 which a liquid heating medium is made to flow so as to pass in a serpentine direction round the pipes *a* and *b*; the ribs *e* serving at the same time to conduct the heat of the medium directly to the said pipes, substantially 70 as described.

3. The combination of a discharge-pipe *a* for liquid gas, having an oblique passage *g*, a pipe *b* into which pipe *a* fits, having ribs *e*, and a closed casing *c* surrounding pipe *b* and 75 through which a heating fluid is made to flow, substantially as described.

In witness whereof I have hereunto set my hand in presence of two witnesses.

LUDWIG VON ORTH.
